UNITED STATES PATENT OFFICE

159,901

FRONT FOR A SPECTACLE FRAME

Walter Goldstein, New York, N. Y.

Application May 21, 1949, Serial No. 2,799

Term of patent 3½ years

(Cl. D57—1)

To all whom it may concern:

Be it known that I, Walter Goldstein, a citizen of the United States of America and a resident of New York, in the county of New York and State of New York, have invented a new, original, and ornamental Design for a Front for a Spectacle Frame, of which the following is a specification, reference being had to the accompanying drawing forming a part thereof.

In this drawing:

Figure 1 is a front elevational view of a front for a spectacle frame, showing my new design;

Figure 2 is a top plan view of the same.

The essential features of my design reside in the metal ornamental strip and its placement immediately above the openings.

I claim:

The ornamental design for a front for a spectacle frame, as shown and described.

WALTER GOLDSTEIN.
